United States Patent

Des. 234,383
Patented Feb. 25, 1975

234,383

CHAIR

William H. Tacke, Wyoming, Mich., assignor to Curtis
Products Limited, Cobourg, Ontario, Canada

Filed June 19, 1972, Ser. No. 263,993

Term of patent 14 years

Int. Cl. D6—01

U.S. Cl. D6—31

FIG. 1

FIG. 2

FIG. 3

FIG. 4

FIG. 5

FIG. 6

FIG. 1 is a slightly elevated, generally front perspective view of the chair embodying my design;

FIG. 2 is a side elevational view of the chair;

FIG. 3 is a front elevational view of the chair;

FIG. 4 is a rear elevational view of the chair;

FIG. 5 is a top plan view of the chair; and

FIG. 6 is a slightly elevated, generally rear perspective view of the chair.

Characteristic features of the design include a somewhat triangular-shaped, slender, tubular back support and armrest member disposed at each side of the chair, which member begins along the side of the backrest, extends downwardly to the seat and then forwardly along the side of the seat, curves upwardly through a relatively wide arc and then sweeps rearwardly and upwardly at an inclined angle to define an armrest, the armrest stopping short of that portion of the tubular member

which extends along the side of the backrest to create a gap therebetween.

I claim:

The ornamental design for a chair, substantially as shown and described.
